UNITED STATES PATENT OFFICE

ASGER EILERSGAARD, OF CHICAGO, ILLINOIS, ASSIGNOR TO LINK-BELT COMPANY,
OF CHICAGO, ILLINOIS, A CORPORATION OF ILLINOIS

POSITIVE-CROWD MECHANISM

Application filed May 25, 1928. Serial No. 280,430.

My invention relates to improvements in positive crowd mechanism for shovels and the like and has for one object to provide in connection with a dipper shovel or excavator having a single source of power which operates all the various mechanisms, a positive crowd and controlling means therefor. A further object of my invention is to provide in connection with a shovel mechanism and positive crowd therefor, new and improved means for controlling and manipulating the shovel. Other objects of my invention will appear from time to time throughout the specification and claims.

15 My invention is illustrated more or less diagrammatically in the accompanying drawings, wherein—

Figure 1 is a side elevation;

Figure 2 is a plan view.

20 Like parts are indicated by like characters throughout the specification and drawings.

A is a truck supported on idler rollers A¹ over which travel the endless crawler chains A², there being one on each side of 25 the truck, this chain being driven by a sprocket A³. A⁴ is a turn table on the truck associated with a fixed swinging gear A⁵. A⁶ is a swinging or working platform being supported on the turn table A⁴ by means of a 30 series of rollers A⁷. A⁸ is a pinion on the turn table A⁶ in mesh with the gear A⁵ whereby when the pinion is rotated the working platform A⁶ may be rotated on the truck.

B is a cab or housing mounted on the platform A⁶. It contains preferably an internal combustion engine B¹ which drives by means of a train of gears B² B³ a drum shaft B⁴ mounted for rotation in the hoisting gear frame B⁵. Mounted on the drum shaft is a 35 hoisting drum B⁶, having at one end a clutch drum and clutch B⁷ whereby this hoisting drum may be connected to and disconnected from the drum shaft B⁴ for driving. On 40 the other end of the drum B⁶ is a brake and brake drum B⁸ whereby rotation of the hoisting drum may be controlled. On the same shaft B⁴ is a crowd drum B⁹ associated with a brake and brake drum B¹⁰ and with 45 a clutch and clutch drum B¹¹ whereby the

crowd drum B⁹ may be driven in the same direction as the shaft B⁴.

C is a reversing shaft mounted for rotation in the hoisting gear frame B⁵. Rigidly mounted on the shaft C is a sprocket C¹ over which travels a sprocket chain C² which chain also travels over a sprocket C³ rigidly mounted on the drum B⁹ so that the shaft C and the drum B⁹ always rotate in unison. C⁴ is a gear rigidly mounted on the shaft B⁴ and in mesh with a gear C⁵ on the shaft C. C⁶ is a clutch and clutch drum interposed between the gear C⁵ and the shaft C so that the gears C⁴ and C⁵ always rotate in unison with the shaft B⁴. There being one gear on each shaft, 55 obviously when the shaft B⁴ is driven through the chain, it travels in one direction and when driven through the gears it travels in the opposite direction. C⁷ is a sprocket on the shaft C over which travels a chain C⁸ which chain also travels over a sprocket C⁹, this chain being held tight by means of an idler sprocket C¹⁰ pivoted on the lever C¹¹ and adjusted by means of a turn buckle and screw C¹².

75 Projecting forwardly from the front edge of the platform A⁶ on opposed ends thereof are brackets D. These brackets carry pins D¹ upon which are pivoted yokes D², which yokes are attached to the inner end of the boom D³, the boom being tapered so as to be wider at its lower end where it is pivoted on the working platform, than it is at the upper end. D⁴ is a shipper shaft mounted for rotation on and extending transversely across the boom D³. This boom is centrally apertured as at D⁵ to permit longitudinal travel of the dipper handle or stick D⁶. A bridle D⁷ pivoted on the shaft D⁴ in which the dipper handle is slidably mounted furnishes a floating pivot 80 for the dipper handle. D⁸ is a shipper rack extending along that side of the handle adjacent the shaft D⁴ and this rack is in mesh with a shipper pinion D⁹ on the shipper shaft D⁴ by which rotation of the pinion causes 85 longitudinal translation of the dipper handle.

E is a sprocket rigidly mounted on the shipper shaft D⁴. E¹ is a chain belt traveling around said sprocket extending downwardly along the boom to travel around a sprocket E² 100

which sprocket is rigidly mounted on the shaft E³, which shaft also carries the sprocket C⁹. The two sprockets being tied together so that the rotation of the sprocket C⁹ always results in rotation of the sprocket E². E⁴ is a take-up sprocket pivoted on the link E⁵ and associated with a turn buckle and pin E⁶ whereby the sprocket E⁴ may be projected or retracted to maintain proper tension in the chain E¹. It will be noted that the two brackets upon which the boom are pivoted are totally separated and disassociated from the shaft E³ and the sprockets E² and C⁹ though the axis of rotation of all three of them are on the same line.

F is a dipper bucket mounted on the end of the boom D⁶. It has the usual pivoted floor or bottom F¹ and cutting teeth F² and is equipped with a pivoted yoke F³. Extending upwardly from this yoke is a cable F⁴ to pass up over a sheave F⁵ at the end of the boom and thence down about the hoisting drum B⁶. F⁶ is an A-frame projecting upwardly from the working platform A⁶. F⁷ are cables extending from the A-frame around sheaves F⁸ and thence back over sheaves F⁹ on the A-frame F⁶ and thence down to a drum F¹⁰ whereby the boom may be supported and the angle of the boom controlled though as a general proposition the boom remains at a fixed angle during operation.

The use and operation of my invention are as follows:

The motor drives the drum shaft through the train of gears indicated and this drum shaft always rotates in the same direction. When the operator wishes to operate the bucket, he manipulates the clutch to cause the drum shaft to rotate the drum to raise the bucket. When the bucket is raised, he can either hold it by the brake and throw out the clutch or throw out the clutch and let it drop but gravity does the work. There is no need of any reversing mechanism in connection with the dipper or bucket hoist.

Since the gear on the drum shaft is rigid thereon, it always turns with it and turns the other gear on the reversing shaft, therefore these two gears are always in rotation. The chain leading from the sprocket on the drum shaft to and around the sprocket on the reversing shaft is connected to the drum shaft by the clutch associated with the drum sprocket. Only when this clutch is engaged is this sprocket chain driven by the drum shaft. All other times it idles with the reversing shaft. The clutches controlling the sprocket chain and controlling the two gears are so arranged that when one is in, the other is out though they both may be out and neutral at the same time. Thus a manipulation of the control lever will cause the reversing shaft to rotate in either a forward or reverse direction in response to rotation of the drum shaft. The driving connection between the

reversing shaft and the sprocket concentric with the boom and between such sprocket and the shipper shaft is of course obvious. The two clutches may be manipulated to drive the shipper shaft in either direction and thus to crowd out or retract the boom as the case may be.

I claim:

1. In an excavating machine, a working platform, a boom pivoted thereon at two widely spaced points, a dipper handle slidable in the boom, a dipper shaft associated therewith to drive it, a jack shaft interposed between and concentric with the two pivot connections of the boom on the working platform, a sprocket and chain drive interposed between the shipper shaft and the jack shaft and means for driving the jack shaft.

2. In an excavating machine, a working platform, a boom pivoted thereon at two widely spaced points, a dipper handle slidable in the boom, a dipper shaft associated therewith to drive it, a jack shaft interposed between and concentric with the two pivot connections of the boom on the working platform, a sprocket and chain drive interposed between the shipper shaft and the jack shaft and means for driving the jack shaft, said means comprising a reversing shaft, a sprocket and chain connection between it and the jack shaft and means interposed between the working shaft and the motor for driving it selectively in opposite directions.

3. In an excavating machine, a working platform, a boom pivoted thereon, the pivot connection between the boom and platform comprising separate spaced brackets on boom and platform, pivot pins one for each pair of brackets to hold the brackets on boom and platform together, a dipper handle slidable and rotatable on the boom, a shipper shaft associated therewith, a jack shaft on the platform concentric with the pivot axis of the boom and a sprocket and chain connection between the jack shaft and the shipper shaft.

4. In an excavating machine, a working platform, a boom pivoted thereon, the pivot connection between the boom and platform comprising separate spaced brackets on boom and platform, pivot pins one for each pair of brackets to hold the brackets on boom and platform together, a dipper handle slidable and rotatable on the boom, a shipper shaft associated therewith, a jack shaft on the platform concentric with the pivot axis of the boom and a sprocket and chain connection between the jack shaft and the shipper shaft, the jack shaft being located between the two points where the boom is pivoted on the platform.

5. In an excavating machine, a working platform, a boom pivoted thereon, the pivot connection between the boom and platform comprising separate spaced brackets on boom and platform, pivot pins one for each pair

- of brackets to hold the brackets on boom and platform together, a dipper handle slidable and rotatable on the boom, a shipper shaft associated therewith, a jack shaft on the platform concentric with the pivot axis of the boom and a sprocket and chain connection between the jack shaft and the shipper shaft, the jack shaft being in line with between but altogether out of contact with the two pivot
- 5 shafts.
6. In an excavating machine, a working platform, a boom pivoted thereon, the pivot connection between the boom and platform comprising separate spaced brackets on boom
- 10 and platform, pivot pins one for each pair of brackets to hold the brackets on boom and platform together, a dipper handle slidable and rotatable on the boom, a shipper shaft associated therewith, a jack shaft on the platform concentric with the pivot axis of the boom and a sprocket and chain connection between the jack shaft and the shipper shaft, the jack shaft being located between the two points where the boom is pivoted on the platform, driving means for the jack shaft including a reversing shaft.
- 15 7. In an excavating machine, a working platform, a boom pivoted thereon, the pivot connection between the boom and platform comprising separate spaced brackets on boom and platform, pivot pins one for each pair of brackets to hold the brackets on boom and platform together, a dipper handle slidable and rotatable on the boom, a shipper shaft
- 20 associated therewith, a jack shaft on the platform concentric with the pivot axis of the boom and a sprocket and chain connection between the jack shaft and the shipper shaft, the jack shaft being in line with, between but altogether out of contact with the two pivot
- 25 shafts, driving means for the jack shaft including a reversing shaft.
8. A hoisting mechanism for excavating machines and the like comprising a supporting frame, a drum shaft, and means for positively driving it, a pair of drums rotatable on the shaft, a hoisting cable wound about one of said drums, a sprocket mounted on the other, clutches and brakes associated with
- 30 each of the drums whereby each drum may be separately driven from the drum shaft, a reversing shaft parallel with the drum shaft, a gear train interposed between the drum shaft and the reversing shaft, a sprocket on
- 35 the reversing shaft and an endless chain driven over both said sprockets, clutches associated with the gear train and the sprocket and chain train whereby the reversing shaft may be driven selectively in either direction
- 40 by the drum shaft, and may be disconnected therefrom.
- 45 Signed at Chicago, county of Cook, and State of Illinois, this 21st day of May, 1928.
- 50 ASGER EILERSGAARD.
